5 Claims. (Cl. 242—55.1)

1

The present invention relates to a method and mechanism for producing laps formed of textile fibres in scutching and sliver lap machines.

Production of laps from cotton tuft on scutching machines or from card slivers on sliver lap machines usually includes the step of rolling up the lap between two fluted rollers on a cylinder whose ends are engaged and which is depressed by the heads of lap racks. The racks are preferably connected by means of a pinion with a brake. If pressure is applied to the lap in this manner, it is initially very great and decreases with increasing size of the lap, because the pressure exerted by the brake on the cylinder changes with the changing position of the pressure heads. The interior layers of the lap are therefore closer to each other than the outer layers which are consequently looser; the outer layers shift relatively to each other during the roll up operation causing a milling movement which makes the lap less uniform and impairs subsequent unrolling of the lap. The conventional brake arrangements for the racks cause a jerky upward movement because the adhesion friction of the brake is overcome only after a certain pressure has been built up on the heads of the racks by the lap.

It is an object of the present invention to provide a method and means for exerting a constant pressure on the individual layers of a lap while it is formed on a scutching or sliver lap machine. According to the invention, the pressure with which the spindle is pressed against the lap rollers is automatically increased with increasing diameter of the lap to counter-balance the reduction of pressure between the spindle and the lap rollers due to increasing diameter of the lap. The upward movement of the lap roll is used for actuating a piston in a cylinder which communicates with a pressure vessel. The system comprising the cylinder and the vessel is closed and contains a gas or air whose pressure is increased upon movement of the piston due to rising of the roll carrier. No auxiliary pump is needed to produce the required pressure for constraining the vertical movement of the lap roll.

A further object of the invention resides in the provision of means for automatically changing the pressure exerted on the lap spindle by

2

the heads of the lap racks in accordance with the distance between the heads and the lap rollers.

Further and other objects of the present invention will be hereinafter set forth in the accompanying specification and claims, and shown in the drawing which, by way of illustration, shows what I now consider to be preferred embodiments of my invention.

10 In the drawing:

Fig. 1 is a part sectional front view of one end of the lap mechanism according to the invention;

Fig. 2 is a part sectional side view of the mechanism shown in Fig. 1;

Fig. 3 is a diagram illustrating the pressure forces in the lap mechanism when the diameter of the lap roll is small;

Fig. 4 is a diagram as Fig. 3, illustrating the forces when the lap roll diameter is great.

Like parts are designated by like numerals in all figures of the drawing.

The lap mechanism comprises a frame 1 on whose ends columns 2 are mounted for supporting the bearings of four superimposed calender rollers 3. Two lap rollers 4 are borne in the forward part of the frame. Adjacent to the ends of rollers 4 are the end plates 5 of the lap bobbin, outside of which the heads 6, provided at the upper ends of draw rods 7, are located. A sleeve 9 carried by the lap rod 8 extends between the end plates 5, the lap A coming from the calender rollers 3 being rolled up on sleeve 9. Rod 8 rotates in bearings provided in the heads 6, and the sleeve 9 and end plates 5 rotate with the rod. The lap B is rotated by the rollers 4. Each draw rod 7 carries at its lower end a power piston 10 slideable in a cylinder 11 containing compressed air. The flow of the air to and from both cylinders 11 is controlled by a control piston 12 in a cylinder 13, the piston 12 being actuated by a pedal lever 14. The pressure cylinders 11 are connected for air flow with the control cylinder 13 by means of conduits 15, 16, and 17. In the latter is a check valve 18 blocking flow of air from the pressure cylinders 11 to the control cylinder. Compressed air is supplied from a closed tank 19 from which it flows through conduit 20 to the control cylinder 13. Compressed air is supplied to tank 19 through conduit 23

comprising a reducing valve 22. A check valve in conduit 23 between valve 22 and tank 19 prevents flow of air from the latter.

By depressing pedal 14", the arm 14' of lever 14 is lifted, and piston 12 is moved to its upper position which is illustrated and in which the conduits 20 and 15 are interconnected for air flow. An air relief opening 13' is provided in the top of cylinder 13. In the illustrated position, pressure is applied to the top side of piston 10, 10 which pressure is transferred through the draw rods 7, the heads 6, and the lap rod 8 to the lap B. The growing lap pulls pistons 10 upward, whereby the air above the pistons is forced back into tank 19 in which the air is retained by the check valve 21, causing increase of air pressure in tank 19 and above piston 10 in cylinder 11.

As seen in Figs. 3 and 4, the pressures K and K' produced by the pull Z in rod 7 and acting on the rollers 4 decrease with increasing diameter of the lap B, because of the decrease of the angle enclosed by the forces K and Z and K' and Z from a value α to a value α' , respectively.

The capacity of tank 19 is made so that the pull Z is increased proportionately to the decrease of angle α and the forces K are substantially the same at all lap diameters. This assures constant pressure during roll up of lap B. The draw rods 7 and the heads 6 move steadily and not jerkily as in the conventional machines, because the operating air is compressed steadily.

When a lap is completed, the device is stopped by moving the pedal lever 14 to the position indicated by a dash-dot line in Fig. 2, which causes lowering of piston 13. The air in the upper parts of cylinders 11 can now escape through conduit 15 and aperture 13'. At the same time, air flows from tank 19 into the control cylinder 13 and through conduits 16 and 17 into the pressure cylinder 11 below piston 10. Conduits 16 and 17 are connected with the bore of a lateral protuberance 13" in cylinder 13, the bore terminating in cylinder 13 at such a point that it communicates with the space left by the throat 12' of piston 12 when the latter is in its lower position. The air pressure below piston 10 moves the latter quickly upward, lifting the lap B from the rollers 4, through rods 7, heads 6, and rod 8. The latter is pulled out of the heads 6 by gripping its hand wheel 8', Fig. 1, and the completed lap B can be removed from the machine. After insertion of a new sleeve and of rod 8 into the heads 6, pedal 14" is depressed to its lower position, whereupon control piston 13 is again moved into its operating position. Compressed air flows from tank 19 through conduits 20 and 15 to the upper part of the pressure cylinder 11, quickly lowering the pistons 10 and expelling the air below the pistons 10 through conduits 16 and 17 and an aperture 24 in the lower end of cylinder 13. A throttle screw 25 controls the escape of air through aperture 24 so that the speed at which piston 10 and consequently the new sleeve 9 are lowered, can be regulated. As soon as piston 10 blocks the mouth of conduit 15 in cylinder 11, no air can escape from the lower part of cylinder 11, escape of air through conduit 17 being slowed by valve 18. Piston 10 and the parts connected therewith gradually come to a standstill because valve 18 is not absolutely tight, and the sleeve 9 is set gently on the rollers 4. The lap mechanism is now ready to roll up a new lap.

The result obtained by the pneumatic device described above can also be produced by mechanical means. In this case, the draw rods 7

would have to be provided with a brake controlled by a cam, so that its braking effect increases with increasing diameter of the lap and the force K acting on the lap remains the same at all diameters of the lap.

Instead of compressed air, a liquid can be used whose pressure is controlled by positively operated throttle valves so that the pressure increases with increasing diameter of the lap.

While I believe the above described embodiments of my invention to be preferred embodiments, I wish it to be understood that I do not desire to be limited to the exact details of method, design, and construction shown and described, for obvious modifications will occur to a person skilled in the art.

I claim:

1. Device for producing a lap roll from slivers of textile fibers, comprising a sleeve on which the lap is rolled up, a lap rod extending through said sleeve, head means supporting said rod, two rotating lap rollers supporting and frictionally engaging the lap rolled up on said sleeve for rotating the lap roll, a draw rod connected with each of said head means for drawing said head means and sleeve toward said lap rollers, a power piston connected with each rod, a stationary pressure cylinder for each power piston, and a closed tank containing an operating medium and being connected for medium flow with said cylinders, the operating medium being forced from said cylinders into said tank upon movement of said power pistons in said cylinders because of increasing diameter of the rolled up lap.

2. Device as set forth in claim 1, comprising a control cylinder interposed for medium flow between said tank and said pressure cylinders, a control piston in said control cylinder for controlling medium flow through the latter, and actuating means connected with said control piston for moving said control piston in said control cylinder.

3. Device according to claim 2, said control piston affording flow of medium from said pressure cylinders on one side of said power pistons into said tank when the control piston is in one of its extreme positions and affording flow of medium from said tank into said pressure cylinders at the other side of said power pistons when said control piston is in its other extreme positions.

4. Device for producing a lap roll from slivers of textile fibers, comprising a sleeve on which the lap is rolled up, a lap rod extending through said sleeve, head means supporting said rod, two rotating lap rollers supporting and frictionally engaging the lap rolled up on said sleeve for rotating the lap roll, a draw rod connected with each of said head means for drawing said head means and sleeve toward said lap rollers, a power piston connected with each rod, a stationary pressure cylinder for each power piston, a tank containing an operating medium, a control cylinder connected for medium flow with said tank, first conduit means connecting said control cylinder for medium flow with the draw rod end of said pressure cylinder, two second conduit means connecting said control cylinder for medium flow with the other end of said pressure cylinder and adapted to be consecutively closed by said power piston moving toward said other end, a control piston in said control cylinder for controlling medium flow therethrough, actuating means connected with said control piston for moving said control piston in said control cylinder, said con-

trol piston when in one of its extreme positions affording flow of medium through said two second conduit means and said control cylinder to one of said outlets and from said tank into said pressure cylinder through said first conduit means for moving the power piston in said pressure cylinder toward the end with which said two second conduit means are connected, and throttle means in the one of said two second conduit means which is closed last by the so moved 10 power piston for cushioning the stop of the power piston caused by closing of said two second conduit means.

5. A lap-winding machine comprising a roll carrier raised by the increasing diameter of the 15 roll, a cylinder, a piston movable in said cylinder and connected with said carrier, and a closed air

tank communicating with and receiving air from said cylinder upon movement of said piston in said cylinder due to rising of said carrier.
